B. E. STEWART, OF SOMERVILLE, MASSACHUSETTS.

DISPLAY-RACK.

1,300,942.

Specification of Letters Patent.

Patented Apr. 15, 1919.

Application filed July 10, 1918. Serial No. 244,298.

To all whom it may concern:

Be it known that I, FREDERICK M. ETHEridge, a citizen of the United States, residing at Boston, in the county of Suffolk and 5 State of Massachusetts, have invented new and useful Improvements in Display-Racks, of which the following is a specification.

This invention is embodied in certain improvements relating to a display rack embodying the invention pointed out in the claims of Patent No. 1,259,005, dated March 12, 1918. The object of said improvements is to increase the strength, durability and convenience of operation of a rack embodying the said invention.

Of the accompanying drawings forming a part of this specification,—

Figure 1 is a side elevation of the improved display rack.

20 Fig. 2 is an end elevation of the same, portions being broken away.

Fig. 3 is a section on line 3—3 of Fig. 1.

Fig. 4 is an enlargement of a portion of Fig. 2.

25 Fig. 5 is a side elevation of the merchandise carrier hereinafter described, detached from the supporting frame.

Fig. 6 is a fragmentary view showing an enlargement of a portion of Fig. 5.

30 Fig. 7 is a section on line 7—7 of Fig. 5.

Fig. 8 is a fragmentary view showing an enlargement of another portion of Fig. 5.

Fig. 9 is a transverse section of one of the channelled bars hereinafter described, and 35 an elevation of portions of one of the merchandise carriers engaged with said bar.

Fig. 10 is a top plan view of a portion of one of said track bars, and shows portions of three of the merchandise carriers.

40 Fig. 11 is a section on line 11—11 of Fig. 9, and an elevation of parts at the left of said line.

Fig. 12 is a fragmentary top plan view hereinafter referred to.

45 Fig. 13 is a fragmentary view showing the channelled track bar in side elevation, one of the side flanges of said bar being removed.

The rack embodying the improvements hereinafter described includes, as in the 50 patent above mentioned, two rigid end frames, each including a base member 12, and vertical standards 13 attached at their lower ends to the base member and projecting upwardly therefrom. The standards 13 are preferably of metal tubing and are ex-

tended at their lower portions through the base member 12, and connected at their lower ends as by elbows 16 to horizontal tubular rods 17 which rigidly connect the two end frames and are in close proximity to the 60 floor on which the structure rests. The structure is preferably supported by casters 18 suitably connected with the base members 12. To the upper ends of the standards 13 are rigidly connected the ends of horizontal 65 channelled track bars each designated as a whole by the reference numeral 19, said bars being spaced apart and extending horizontally from one end frame to the other, so that they constitute rigid connections between the upper portions of the end frame. 70

Each bar 19, as here shown, includes a central web or neck 19^a and outer and inner flanges 19^b and 19^c projecting downwardly from said neck. 75

To the outer flange 19^b is attached an upwardly facing weight-supporting track member 20, preferably having a raised rib 21 adapted to engage a grooved trolley 22 connected with the merchandise carrier hereinafter described, said trolley rotating on a horizontal axis. The inner flange 19^c constitutes a laterally facing track member adapted to coöperate with a thrust bearing roller 23 connected with the said merchandise carrier and rotating on a vertical axis. 80

Each channelled track bar 19 is secured at opposite ends to two standards 13, the standards being provided with fixed collars or enlargements 25 to which the bars 19 are 90 attached by screws 25^a. The collars 25 have ears 26 which are perforated to receive the ends of elongated truss rods 27, extending through the channels of the bars 19 from end to end, as indicated by dotted lines in Fig. 95 1. The end portions of the truss rods 27 are raised and screw-threaded, and provided with nuts 28 which are seated on the ears 26, the latter constituting abutments for heads formed on the truss rods by said nuts. 100 The truss rods stiffen the channelled bars 19 and prevent them from sagging at the center under the weight of the merchandise carriers and their loads, the end portions of the truss rods also constituting bearings which 105 assist the screws 25^a in supporting the weight of the bars 19. The depressed central portions of the truss rods bear on downwardly facing abutments 30 (Figs. 1 and 13) attached to the bars 19. 110

The rack includes a plurality of merchandise carriers supported by the track members 20 and trolleys 22, each carrier being preferably constructed as follows:

- 5 31 (Fig. 5) represents a hanger bar constituting a member of a merchandise carrier and provided at its end portion with brackets 32 having bearings for the axles of the trolleys 22 and rollers 23 above described.
- 10 34 represents an elongated rod constituting another member of the carrier and centrally connected with the hanger bar 31 by a vertical king bolt 35. The rod 34 is therefore adapted to swing in a horizontal plane, so
- 15 that it may extend either crosswise or lengthwise of the frame. Fig. 1 shows three carriers adjusted with the rods 34 extending crosswise of the frame, and another rod 34 extending lengthwise of the frame. Provision
- 20 is made, therefore, for storing the rods side by side compactly at one end portion of the frame, and utilizing the remaining portion of the frame to contain the carrier, the rod 14 of which extends lengthwise of the frame
- 25 so that the entire outer side of a rug *r* supported by the rod is exposed to view. I have provided means for locking the rod 34 to the hanger bar 31 to prevent an independent swinging movement of the rod.
- 30 Said means may be embodied in a bolt 36 (Fig. 8) movable in the rod 34 and adapted to enter a socket in the hanger bar 31, and a bell crank lever 37 fulcrumed on the rod 34, and a spring 38 normally confining the
- 35 lever and bolt with the lever raised or projected. The bolt 36 may be retracted by means including a bell crank lever 39 (Fig. 5) fulcrumed at an end portion of the carrier at a distance from the lever 37, a rod
- 40 40 connecting the levers 37 and 39, and a pull rod 41 whereby the lever 39 may be moved from the normal position in which it is held by the spring 38.

In a rack adapted to display large rugs

45 the rod 34, which is provided with rug-engaging spurs 42, is located so high above the floor that it cannot be conveniently grasped and moved by an operator standing on the floor. I therefore provide the merchandise carrier with a handle bar 43 which is connected with the rod 34 by transverse bars or frame members 44 and 45. The bar 43 is provided with handles 43' at its ends, adapted to be grasped by the operator.

50 The object of the track members 19° on the channeled bars 19 and the thrust bearing roller 23 on the merchandise carrier, is to enable the carrier to be moved by the application of force to one of the handles 43', or to one end of the rod 34, without such displacement of the trolleys 22 as would cause the sides of their grooves to bind on the tread portion 21 of the track member 20. In other words, the track members 19° and

55 rollers 23 prevent one end of the merchan-

dise carrier from swinging forward when force is applied thereto to move the carrier along the frame. I have found by practical experience that the track members 19° and rollers 23 coöperate with the trolleys 22 70 and track members 20 in such manner that a carrier bearing a heavy rug or rugs can be easily moved along the frame by power applied by the operator to either end of the rod 34, or of the handle bar 43.

To prevent undue wear of the hanger bar 31 and rod 34 by contact with each other, I provide said bar and rod with metallic wear plates 47, as indicated by Fig. 11, in sliding contact with each other.

The longitudinal members 17 may be provided with enlargements 17^a adapted to rest on supporting plates 48 on the floor, as indicated by Figs. 1 and 3.

The channeled bars 17 may be connected by transverse tie-plates 49.

To prevent contact between adjacent suspended rugs I may provide the hanger bars 31 with laterally projecting studs 50, the studs on one bar contacting with the next 90 bar, as shown by Fig. 11.

I claim:

1. A display rack comprising spaced apart horizontal channeled track bars having weight-supporting track members with 95 in their channels, supports engaged with the end portions of said bars, longitudinal truss rods within said channels, having raised end portions seated at opposite ends of the bars, and a depressed central portion 100 seated between the ends of the bars, and merchandise carriers having trolleys adapted to run on said track members.

2. A display rack comprising spaced apart horizontal bars having weight-supporting track members, supports engaged with the end portions of said bars, and merchandise carriers having trolleys adapted to run on said track members, each carrier including a hanger bar carrying said trolleys, 110 and an elongated merchandise-engaging rod pivoted to said hanger bar and adapted to swing relatively thereto in a horizontal plane.

3. A display rack comprising spaced apart horizontal bars having weight-supporting track members, supports engaged with the end portions of said bars, and merchandise carriers having trolleys adapted to run on said track members, each carrier 120 including a hanger bar carrying said trolleys, and an elongated merchandise engaging rod pivoted to said hanger bar and adapted to swing relatively thereto in a horizontal plane, means being provided for 125 releasably locking the rod to the hanger bar to prevent a swinging movement of the rod.

4. A display rack comprising spaced apart horizontal bars having weight-supporting track members, supports engaged 130

- with the end portions of said bars, and merchandise carriers having trolleys adapted to run on said track members, each carrier including an elongated merchandise-engaging rod supported by said trolleys, means being provided for preventing either end of said rod from swinging foward when pressure is applied thereto to move the carrier on the track members.
- 5 5. A display rack comprising spaced apart horizontal bars having weight-supporting track members, supports engaged with the end portions of said bars, and merchandise carriers having trolleys adapted to run on said track members, each carrier including an elongated merchandise-engaging rod supported by said trolleys, a handle bar below said rod and rigid transverse connections between said bar and rod, means being provided for preventing either end of said rod and handle-bar from swinging forward when pressure is applied to move the carriers on the track members.
- 10 6. A display rack comprising spaced apart horizontal channeled track bars having outer flanges provided with weight-supporting track members, and inner flanges constituting thrust bearing track members, supports engaged with the end portions of said bars, and merchandise carriers having trolleys adapted to run on said weight-supporting track members and rollers adapted to run on said thrust bearing track members, said carrier including a hanger bar carrying said trolleys, an elongated merchandise-engaging rod pivoted to said hanger bar and adapted to swing relatively thereto in a horizontal plane, a handle-bar below said rod, and rigid transverse connections between said bar and rod, the hanger 35 bar and rod being provided with complementary releasable locking means adapted to prevent an independent swinging movement of the rod.
- 15 7. In testimony whereof I have affixed my 40 signature.
- 20

FREDERICK M. ETHRIDGE.
